(57) **CLAIM**

I claim the ornamental design for vest, as shown and described.

DESCRIPTION

FIG. 1 is a perspective view of the vest showing my new design;

FIG. 2 is a front view thereof;

FIG. 3 is a right side view thereof; and,

FIG. 4 is a top view thereof.

The broken lines shown in FIG. 1 are included for the purpose of illustrating environmental structure and form no part of the claimed design.
